UNITED STATES PATENT OFFICE.

ERNEST PENBERTHY, OF DETROIT, MICHIGAN, ASSIGNOR TO CHICAGO PNEUMATIC TOOL COMPANY, OF NEW YORK, N. Y., A CORPORATION OF NEW JERSEY.

TOOL RETAINER.

Application filed September 3, 1921. Serial No. 498,500.

The invention relates to tool retainers more particularly designed for use in connection with rock drills and functioning to prevent disengagement of the drill steel when 5 the tool is being withdrawn.

The invention consists in the novel construction as hereinafter set forth:

In the drawings,—

Figure 1 is a side elevation of a rock 10 drill to which my improvement is applied.

Figure 2 is a cross section substantially on line 2—2 Figure 1, showing the retainer in locked engagement with the drill-stem.

Figure 3 is a longitudinal section through 15 a portion of the tool showing the retainer in elevation.

Figure 4 is a bottom plan view of the tool and retainer.

Figure 5 is an elevation of the sheet metal 20 blank from which the retainer is formed.

A is a pneumatic tool of any suitable construction. B is the drill steel having the polygonal portion C for engaging a rotary socket D, and E is the shank of the piston 25 which impinges against the portion C. The thrust of the tool when pressed toward the work is transmitted from the piston directly to the drill steel. A collar F upon the drill steel cooperates with the retainer to prevent 30 disengagement of the steel when the tool is withdrawn from the work.

To form a simple construction of retainer I employ a sheet metal blank G, substantially of the form shown in Figure 5. The central 35 portion H of this blank is bent to form a yoke for embracing the steel D and forming a shoulder for engaging the collar F to hold the same from outward movement. Upon the opposite side of this central portion the blank is return bent, as indicated at I and I', and arms J J' extend upward from the return bent portions on diametrically opposite sides of the tool. The upper ends of these arms are apertured at K and engage trunnions L upon a collar M, which collar is sleeved upon the lower end portion N of the tool and is resiliently supported by a spring O. The abutment for the spring O is formed by a second collar P which has 45 entrance slots Q therein for passing over projecting lugs R on the portion N. These lugs R are engageable with recesses S in said collar when the latter is given a partial rotation and thus abutment is secured from 50 disengagement.

From the parts thus far described it will be understood that the arms J J' are formed to swing upon the trunnions L so as to move the yoke H either into a position for engagement with the collar F or into position 60 where it will clear said collar. In each of these positions the retainer is held from accidental displacement by bearing against lugs T on the tool casing and to this end the upper ends of the arms J have angular faces 65 U U' for engaging said lugs in the respective positions of adjustment. The resilient pressure of the spring O holds the arms against said lugs but permits the swinging of the retainer by the application of lateral pressure thereto. To prevent the retainer from accidentally swinging out of engagement with the drill steel when an outward 70 pull is exerted thereon, locking shoulders V V' are formed on the yoke H. These, as 75 shown, are formed by portions W W' which are of greater width than the central portion H and which are so positioned as to be on the opposite side of the axis of the steel and engageable with the collar. Thus when the tool is drawn outward the collar F will slide from its normal position against the socket D into position where it bears against the yoke H and in this position the shoulders V V' will prevent swinging of the yoke into disengaged position, 80 on the other hand, when the collar is in normal position there is nothing to interfere with the outward swing of the retainer so that the steel may be detached or replaced 85 at any time.

What I claim as my invention is:

1. The combination with a socket holder, a socket and a tool having a shank engaging said socket and a collar for bearing against the end of the same, of a retainer formed from a sheet metal blank having a central U-shaped portion for embracing said tool and forming a bearing for engaging said collar, said U-shaped portion having its ends of greater width to form shoulders for engaging the periphery of said collar to prevent lateral disengagement from the tool, return-bent portions on opposite sides of said U-shaped portion, and arms extending from said return-bent portions on opposite sides of said socket holder and pivotally mounted upon the same to permit of swinging of said retainer into and out of engagement with the tool.

2. The combination with a socket holder, a socket and a tool having a shank for engaging said socket and a collar for bearing against the end of the same, of a retainer formed from a sheet metal blank of substantially U form having parallel arms and a connecting portion, the latter being of greater width at its outer ends than at the center, said blank being bent in the central portion thereof to embrace said shank, the portions of greater widths forming stops for engaging the periphery of said collar on the opposite side of the axis of said shank, and the portions beyond said central bent portion being return-bent to arrange said parallel arms with their flat faces in parallelism and embracing said socket holder, and pivots mounted on said socket holder and projecting laterally therefrom to engage apertures in the upper ends of said arms.
3. In a device of the class described, the combination with a tool holder and a tool having a collar, of a retainer blanked from sheet metal having a central portion bent to embrace the tool and forming a bearing for engaging said collar, said central portion having adjacent parts of greater width forming stops for engaging the periphery of said collar on the opposite side of the axis of said tool, said retainer having arms extending from said central portion on opposite sides of said holder, a collar sleeved over said holder with which said retainer arms have pivotal connection, lugs on said holder extending outwardly thereof, the ends of
4. In a device of the class described, the combination with a tool holder and a tool having a collar, of a retainer blanked from sheet metal having a central portion bent to embrace the tool and forming a bearing for engaging said collar, said central portion having adjacent parts of greater width forming stops for engaging the periphery of said collar on the opposite side of the axis of said tool, said retainer having arms extending from said central portion on opposite sides of said holder, a collar sleeved over said holder with which said retainer arms have pivotal connection, the ends of said arms extending beyond said sleeved collar and having flats arranged to engage projecting abutment faces on said holder, a coiled spring surrounding said holder engaging said sleeved collar for yieldingly retaining said arm ends against said faces, and an abutment collar for said spring slidable over said holder in one position of angular adjustment and having locking engagement therewith in another position of angular adjustment.

In testimony whereof I affix my signature.

ERNEST PENBERTHY.
